UNITED STATES PATENT OFFICE

157,349

CASING FOR AUTOMOBILE DIRECTIONAL SIGNAL

Rene Daon, East Norwalk, Conn., assignor to
Yankee Metal Products Corporation, Norwalk,
Conn., a corporation of New York

Application April 7, 1949, Serial No. 1,853

Term of patent 14 years

(Cl. D72—1)

To all whom it may concern:

Be it known that I, Rene Daon, a citizen of the United States, and a resident of East Norwalk, county of Fairfield, and State of Connecticut, have invented a new, original, and ornamental Design for a Casing for Automobile Directional Signal, of which the following is a specification, reference being had to the accompanying drawings, forming part thereof:

Fig. 1 is a perspective view of a casing for automobile directional signal showing my new design;

Fig. 2 is a side elevation thereof;

Fig. 3 is a top plan view;

Fig. 4 is a bottom plan view;

Fig. 5 is an elevational view taken from one end; and

Fig. 6 is an elevational view taken from the other end.

I claim:

The ornamental design for a casing for automobile directional signal, as shown.

RENE DAON.
